UNITED STATES PATENT OFFICE.

HARRY T. ANDERSON, OF BUTLER, PENNSYLVANIA, ASSIGNOR TO HARRY VISSERING AND COMPANY, OF CHICAGO, ILLINOIS, A CORPORATION OF ILLINOIS.

RAILWAY DRAFT-GEAR YOKE.

1,401,749.

Specification of Letters Patent. Patented Dec. 27, 1921.

Application filed February 25, 1920. Serial No. 361,079.

To all whom it may concern:

Be it known that I, HARRY T. ANDERSON, a citizen of the United States, and a resident of Butler in the county of Butler and State 5 of Pennsylvania, have invented certain new and useful Improvements in Railway Draft-Gear Yokes, of which the following is a full, clear, and exact description.

The invention relates to railway draft-gear yokes.

The object of the invention is to provide an improved one-piece forged yoke.

The invention consists in the several novel features hereinafter set forth and more particularly defined by claims at the conclusion hereof.

In the drawings: Figure 1 is a perspective of a railway draft gear embodying the invention. Fig. 2 is a detail perspective of 20 the yoke. Fig. 3 is a plan. Fig. 4 a side elevation and Fig. 5 a horizontal section of the yoke. Fig. 6 is a section taken on line 6—6 of Fig. 4. Fig. 7 is a section taken on line 7—7 of Fig. 4.

25 The invention is illustrated as applied to a coupler 9 disposed between a pair of draft-beams 10 (only one of which is shown) a key 11 extending through the coupler shank and through elongated slots in beams 10, as well understood in the art, a draft-gear 14 30 of any suitable construction interposed between the front and rear follower-plates 15 and 16, front stops 12 and rear stops 13, as well understood in the art, and the improved 35 yoke.

Said yoke comprises integral sides 18 and 40 19 and a back 20 and is forged of a channeled bar comprising top and bottom flanges and a connecting web bent and doubled to form said sides and back, the flanges being 45 brought, by such bending, into abutting relation. Adjacent the front end of each yoke-side a transverse slot 25 is formed and the metal at the front of these slots is swaged or 50 upset, as at 26, to reinforce the front-end of said slots, and the key 11 extends through these slots to secure the coupler shank and yoke together. Openings 30 are formed in the sides 18 and 19 and through the web of 55 the channel bar, of which the yoke is formed. These openings are of sufficient length and height for the lateral insertion of the follower-plates 15 and 16 and the draft-gear 14. The front plate 15 is adapted to engage 60 the web of the yoke at the front of openings

30 and the rear plate 16 is adapted to engage the web at the back end of said openings.

In forging the yoke, the flanges of the bar are brought together to form a substantially 60 closed top and bottom for the yoke. If desired, the abutting edges may be forged together. This forms a construction which is narrow and efficient or strong. Those portions of the web of the bar which are disposed in front of slots 30 are bulged outwardly beyond the planes of the upper and lower edges of the yoke formed by the flanges. This provides integral portions between which the coupler shank will fit and 65 which form sides of the coupler shank pocket which are strong and which will form a very compact structure. This is advantageous in getting the clearance, necessary in practice, between the yoke and the draft-beams 10. 70

The method of forging the improved yoke is set forth in an application filed by me of even date herewith, and serially numbered 361,077. 75

The invention exemplifies a forged one-piece yoke with openings for the lateral insertion of the draft-gear and follower plates, and in which the sides extend inwardly above and below the draft-gear into abutting relation, thus forming a compact and efficient structure and also such a yoke in which the web-portions at the front end thereof are bulged outwardly for advantageous connection to the coupler-shank. 80

85 The invention is not to be understood as restricted to the details set forth, since these may be modified within the scope of the appended claims, without departing from the spirit and scope of the invention.

Having thus described the invention, what 90 I claim as new and desire to secure by Letters Patent, is:

1. A one-piece forged draft-gear yoke comprising in combination a front portion having sides spaced apart to receive and formed 95 for keying to a coupler-shank, a back, and longitudinal connecting members in abutting relation between the back and front portion, the yoke having openings adapted for the lateral insertion of the draft-gear. 100

2. A one-piece forged draft-gear yoke comprising in combination a front portion consisting of webs spaced apart to receive and formed for keying to a coupler shank and inwardly extending abutting flanges above 105 110

and below said webs, a back, and abutting top and bottom longitudinal connecting members between the front portion and the back, the yoke having openings for the lateral insertion of the draft-gear.

3. A one-piece forged draft-gear yoke comprising in combination a front portion, a back and longitudinal top and bottom connecting members between the front portion and the back, and having openings adapted for the lateral insertion of the draft-gear, the front portion having outwardly bulged sides formed to receive and formed for keying to a coupler shank.

15. 4. A one-piece forged draft-gear yoke comprising in combination a front portion, a back and longitudinal top and bottom connecting members between the front portion and the back, and having openings adapted for lateral insertion of the draft-gear, the front portion consisting of webs and inwardly extending top and bottom flanges, the webs being bulged outwardly of the flanges and formed to receive and for keying 25 to a coupler shank.

5. A one-piece forged draft-gear yoke comprising in combination a front portion, a back and longitudinal top and bottom connecting members between the front portion and the back, and having openings adapted for the lateral insertion of the draft-gear, the front portion consisting of webs and in-

wardly extending top and bottom flanges, the webs being bulged outwardly of the flanges and formed to receive and for keying 35 to a coupler shank, the connecting members being also formed of inwardly extending flanges.

6. A one-piece forged draft-gear yoke comprising in combination a front portion, a back and longitudinal top and bottom connecting members between the front portion and the back, and having openings adapted for the lateral insertion of the draft-gear, the front portion consisting of webs and inwardly extending top and bottom abutting flanges, the webs being bulged outwardly of the flanges and formed to receive and for keying 45 to a coupler shank.

7. A one-piece forged draft-gear yoke comprising in combination a front portion, a back and longitudinal top and bottom connecting members between the front portion and the back, and having openings adapted for the lateral insertion of the draft-gear, the front portion consisting of webs and inwardly extending top and bottom abutting flanges, the webs being bulged outwardly of the flanges and formed to receive and for keying 55 to a coupler shank, the connecting members being also formed of inwardly extending abutting flanges.

HARRY T. ANDERSON.
